DESIGN FOR A DRINK STIRRER

Roy Charles Baker, Irvington, N. J.

Application November 25, 1938, Serial No. 81,333

Term of patent 14 years

To all whom it may concern:

Be it known that I, Roy Charles Baker, a citizen of the United States and a resident of Irvington, in the county of Essex and State of New Jersey, have invented a new, original, and ornamental Design for a Drink Stirrer, of which the following is a specification, reference being had to the accompanying drawing, forming part thereof.

I claim:

The ornamental design for a drink stirrer, as shown.

ROY CHARLES BAKER.
